TOMLINSON FORT JOHNSON, JR., OF ATLANTA, GEORGIA.

EXPULSION-TYPE REPEATING FUSE.

Application filed August 12, 1922. Serial No. 581,452.

To all whom it may concern:

Be it known that I, TOMLINSON F. JOHNSON, Jr., a citizen of the United States, residing at Atlanta, in the county of Fulton and State of Georgia, have invented new and useful Improvements in Expulsion-Type Repeating Fuses, of which the following is a specification.

This invention relates to improvements in fuses, particularly fuses of the expulsion type.

Primarily, fuses are employed for the purpose of opening the circuits of electrical apparatus when the apparatus is subjected to a heavy overload or to the destructive effects of a short circuit. Fuses, however, will blow or explode whenever there is a temporary rush or surge of current, which occurs most frequently during thunderstorms but may occur in the course of the normal maintenance of a high voltage power line, and when there is nothing the matter with the apparatus. If every time a fuse blew, there was trouble in the apparatus e. g. a short circuit, there would be no necessity for anything but a single fuse since the trouble would have to be corrected before renewing the fuse. However, in the great majority of instances when a fuse blows there is nothing the matter with the apparatus and this is especially true in the case of high voltage long distance transmission lines. If single fuses are used to protect apparatus, for example a transformer, connected with a high voltage line, a temporary rush of current of sufficient energy to blow the fuse will incapacitate the service lines leading from the transformer, resulting in considerable delay before service is restored with consequent annoyance to customers, and in considerable expense and loss in revenue to the company selling the current.

By the present invention, I provide a novel form of fuse which may be called a "repeating" fuse, because after the fuse originally in circuit is blown, the apparatus following a predetermined time interval automatically puts a second fuse in circuit; and if desired, after the second fuse has exploded, a third or any greater number of fuses may be successively cut in to restore service automatically and yet protect the apparatus. Thus the operating expenses are reduced, the loss in revenue due to incapacitated service lines is nearly eliminat-

ed, and generally a much more satisfactory service is given current consumers.

A further advantage of the present invention is that the particular fuse or fuses blown are indicated by the position of the mechanism, so that the inspectors who patrol the transmission system can see at a glance the condition of the apparatus and can renew the fuses before the last fuse blows, which, if allowed to occur, would interrupt service.

The invention has other aims and advantages which will appear in the following description of one preferred and illustrative embodiment thereof.

In the drawings accompanying and forming a part of this specification,

Figure 1 is an elevation of one form of apparatus illustrating the advantages of the invention;

Figure 2 is a fragmentary elevation of the same, on an enlarged scale, and showing the positions of parts when one fuse has blown; and

Figure 3 is a vertical section on the line 3-3 of Figure 1.

Figures 4 and 5 are details representing a modification disclosing the use of a dash pot.

Referring more specifically to the drawing, there is shown by way of illustration, and not of limitation, a base or support 5 which may conveniently be a channel iron fixed upon a tower, pole or other structure (not shown) and disposed horizontally. Upon the channel iron 5 may be secured castings 6 for holding wooden pins 7 upon which are screwed porcelain insulators 8 of any appropriate design. The upper ends of insulators 8 are shown as mounting cast iron caps 9. The parts so far described provide a convenient form of rigid insulating support for the apparatus which embodies my invention.

Secured to or integral with the cast iron caps 9 are vertically extending fuse supports 10, preferably castings, and disposed a suitable distance from each other to inhibit any possible arcing. The fuse supports 10 are shaped so as to hold between them preferably in a horizontal position one or more fuses 11, which may be of any well known type, but are shown as comprising hollow porcelain tubes through each of which a fusible strip of metal 12 is passed. The left hand fuse support 10 (for ex-

ample) is connected to the transmission line by a lug 13 soldered or otherwise secured to cap 9; and the incoming line conductor 14 is made fast to the lug 13. The left hand ends of the fusible elements 12, said ends being indicated at 12^a, 12^b and 12^c, are joined to the adjacent casting 10 so that current from conductor 14 may pass to one or another of the fuses.

10 The drawing depicts three fuses 11 supported parallel to each other, the uppermost being the shortest and the lowermost the longest. It will be obvious however that the invention is not at all limited to the number of fuses employed; any number greater than one will make the apparatus a "repeating" fuse. Nor does it matter whether the longest fuse be the lowest or the highest, or even that the fuses be of different lengths. The invention is independent of any such minor details.

15 At the right hand end of the uppermost fuse 11 there is a metallic cap 15 electrically connected both to the fusible element 12 and to the right hand fuse support 10, the latter connection being by means of a conductor or bond 16, for example. The lower end of said fuse support is joined by a lug 17 and conductor 18 to any electrical apparatus which it is desired to protect. The current normally flows from conductor 14 to the left hand fuse support 10, through 12^a and 12^b, cap 15, bond 16, right hand fuse support 10 and out through lug 17 and conductor 18. In short, all the fuses except the uppermost fuse are normally out of circuit.

20 When the upper fuse blows due to a dangerous surge of current in the power line, my apparatus automatically acts to put the next lower fuse in circuit, but preferably only after a suitable time interval has elapsed. As most clearly shown in Figure 2, the cap 15 swingingly supports a lever 19, as by a pivot 20 and a pair of depending arms 21 between which the lever may swing. At an intermediate point, the lever 19 is mechanically joined as at 22 to the projecting end of fusible element 12, as seen in Figure 1, so that normally the lever 19 is held in a tilted position, with the outer end higher than the end adjacent pivot 20. When the fusible element blows or explodes in the confined space of porcelain tube 11, the lever 19 will no longer have a support for its outer end and will tend to move downwardly into the position of Figure 2, where its outer end 23 is shown making contact with a pair of spring jaws 24. The jaws 24 are generally similar to those employed with knife switches and are carried upon a cap 25 in turn supported on the intermediate fuse 11 and connected to the fusible element thereof.

25 It will be readily understood that when the upper fuse is blown, and lever 19 falls

to make contact with jaws 24, the current flows from the left fuse support 10 through connection 12^b and element 12, through cap 25 and lever 19, arms 21, cap 15, bond 16, fuse support 10, and out through conductor 18.

30 In order to increase the momentum of the fall of lever 19, which is really a switch arm as will be understood and which may hereafter be referred to as such, a weight 26 is provided; and in the showing of the drawings, said weight is slidable on the switch arm 19 and can be held in any adjusted position by means of a set screw 27. Obviously the farther from pivot 20 the weight 26 is put, the more momentum will the switch arm have when it falls to make a good contact with the jaws 24. The weight 26 has another use as will be described later.

35 While the parts so far described form an operative "repeating" fuse, it is preferred that some means be employed to prevent the cutting in of the second fuse at once, so that some time is allowed for normal conditions to be restored in the transmission line. In order to retard the closing of switch 19, a bendable strip of lead or similar metal 28 is interposed between the short end of switch 19 and the cap 15, preferably being attached at each end by screws or the like to legs 21 and switch 19.

40 There is a lever 29 pivoted on element 20 to swing alongside switch 19 and one end of lever 29 is connected to a coil spring 30, whose other end is fixed to cap 15. The lever 29 has an arcuate slot 31 in which a pin or projection 32 on switch 19 may slide when lever 29 is swung. On the slotted part of lever 29 a flat surface 33 is provided, and a screw 34 borne on cap 15 is adapted to bear against the flat surface 33 to adjust the angular position of lever 29. The lever 29 is really a bell crank lever, and the arm thereof connected to spring 30 is in a substantially vertical position when the screw 34 comes in contact with surface 33. At this time the spring 30 is also vertical and its line of force passes through the pivot 20 whereby said spring is in a "dead center position." The screw 34 provides means whereby the lever is prevented from moving past the dead center position when swung in a counterclockwise position, and also provides means for effecting a nice adjustment of the position of lever 29.

45 When the fuse blows the weight 26 on switch 19 causes its outer end to descend at a relatively slow rate, whereupon the pin or projection 32 engages the lower end of slot 31 and therefore swings the lever 29 out of dead center position. This brings spring 30 into action, which quickly swings the slotted end of lever 29 downwardly or in a clockwise direction to bring the upper end of the slot into engagement with pin

32. Then the force of the spring 30 is added to that of gravity to cause the switch 19 to close with considerable force against the spring jaws 24, thus insuring a good contact. The lead strip 28 is provided primarily to check the initial downward movement of switch 19; and if the parts are properly proportioned, the time interval between the opening of the circuit due to 10 blowing of one fuse and closing of the circuit due to cutting in of the adjacent fuse may be made whatever is desired. Instead of the lead strip other braking elements or mechanism may be employed, for 15 example a dash-pot. This is shown in Figures 4 and 5.

It will be clear that by properly proportioning the switch arms 19, 19^a, etc., the weights 26, 26^a, the strips of lead 28, 28^a, 20 and the springs 30, 30^a, the action of the apparatus may be made either very slow, or relatively fast, though it will never operate simultaneously and hence there will always be a time interval between the blowing 25 of one fuse and the restoring of service.

Upon the intermediate fuse the cap 25 is secured as has already been described; and associated with said cap is a switch and switch operating mechanism exactly like 30 the one previously described. The corresponding parts of the second switch mechanism are designated by the letter *a* added to each reference numeral.

When the second fuse blows, the switch 35 19^a descends toward a cap 35 mounted on the end of the lowest fuse and connected to fusible element 12 as shown. The cap 35 mounts a pair of spring jaws 36 adapted to receive between them the outer end 23^a 40 of switch 19^a. Obviously after the second fuse has blown, the current from conductor 14 passes through the third fuse, through both switches 19^a and 19, and so out through conductor 18.

45. The apparatus enables an inspector to tell at a glance the condition of the fuses. With the parts as shown in Figure 1, all the fuses are ready for any emergency; when the apparatus presents the appearance of 50 Figure 2, the uppermost fuse needs renewal. If both switches 19 and 19^a are down, two fuses need to be replaced, while if both switches are down and the line fed from conductor 18 (the service line) is 55 dead, then all three fuses must have attention.

In Figures 4 and 5 wherein a dash pot *P* is shown in lieu of the lead strip, the fuse holds lever 19^a in position. When the fuse 60 melts, the lever 19^a drops down until pin *M* rests on lower lip of part *H*. The latter is pulled slowly toward the dash pot by means of the coiled spring *S* located inside of dash pot until pin *M* falls off the end of lower lip of part *H*. An interval of about

ten seconds elapses between the melting of the fuse and the release of pin *M* from part *H*.

The present invention provides a novel form of apparatus particularly well adapted for outdoor work, large current and high voltages. The parts will operate perfectly in all weather. The construction is rugged and simple and unlikely to get out of order. My repeating fuse protects the apparatus 75 by cutting off the flow of current completely for a determinable time interval, and then automatically reestablishing the service; and this cutting off and reestablishment process may be repeated as often as desired.

While I have described in some detail one illustrative embodiment of my invention, it will be understood that many changes involving omission, alteration, substitution and reversal of parts may be made without departing from the invention, which is best defined in the following claims.

What is claimed is:—

1. Repeating fuse apparatus comprising a pair of fuses, a gravity operated switch between said fuses normally held in inactive position by the fuse which is connected in circuit, means for retarding the initial movement of the switch after the first fuse is blown, and means to accelerate the final movement of the switch to connect the second fuse in circuit.

2. Repeating fuse apparatus comprising a pair of spaced approximately vertical supports, a pair of fuses carried by said supports and arranged approximately horizontally one below the other, the upper fuse being connected in circuit, a gravity actuated switch element normally supported in inactive position by the fusible portion of said upper fuse and adapted to be released automatically to close the circuit through the lower fuse when the upper fuse blows, and means to regulate the time interval during which said switch closes.

3. Repeating fuse apparatus comprising a pair of fuses arranged one above the other, each connected at one terminal to a leading-in wire, and the upper fuse normally connected in circuit, a gravity actuated switch arm normally held inactive by the fusible element in the upper fuse and adapted to be released to close the circuit through the lower fuse, and a binding element serving as a brake to retard the initial movement of said arm during which the circuit remains broken.

4. A switch for repeating fuses including a swinging arm arranged to be released automatically when one fuse blows to close the circuit through the next fuse, and an easily bendable strip of metal connected to said arm to retard its movement.

5. Repeating fuse apparatus comprising

- a pair of fuses one of which is normally in circuit, and a switch member connected mechanically with the fusible part of the fuse normally in circuit, means tending to move said switch toward the other fuse and operable when the first fuse blows, a contact on the second fuse with which said switch is engaged following blowing of the first fuse, whereby the second fuse is put in circuit, and means for operating the switch first slowly and then more rapidly so that a good contact is made with the contact part of the second fuse.
6. Repeating fuse apparatus comprising a pair of fuses one of which is normally in circuit, and a switch and operating mechanism therefor adapted to put the second fuse in circuit when the first fuse blows, said mechanism operating to cause a slow movement of the switch toward circuit closing position followed by a quicker movement, and means whereby the earlier slower movement of the switch may be varied so as to increase or decrease the time interval during which the circuit remains broken.
7. Repeating fuse apparatus comprising a pair of fuses one of which is normally in circuit, a switch swingingly mounted between said fuses, adjustable means for causing said switch to move toward a position to put the second fuse in circuit when the first fuse blows, and means operable after a certain movement of the switch to cause the switch to close with more force and at a greater speed.
8. Repeating fuse apparatus comprising a pair of fuses one of which is normally in circuit, a switch swingingly mounted between said fuses, adjustable means for causing said switch to move toward a position to put the second fuse in circuit when the first fuse blows, means operable after a certain movement of the switch to cause the switch to close with more force and at a greater speed, said second named means being inoperative in the normal positions of the parts, and means for adjusting the sensitiveness of operation of the second named means.
9. Repeating fuse apparatus comprising a pair of fuses one of which is normally in circuit, a switch swingingly mounted between said fuses, adjustable means for causing said switch to move toward a position to put the second fuse in circuit when the first fuse blows, means operable after a certain movement of the switch to cause the switch to close with more force and at a greater speed, said second named means operating wholly independently of the first named means but being put into action wholly by movement of the switch, and adding its force to the force of the first named means to cause the switch to close.
10. Repeating fuse apparatus comprising a pair of fuses one of which is normally in circuit, a switch swingingly mounted between said fuses, adjustable means for causing said switch to move toward a position to put the second fuse in circuit when the first fuse blows, means operable after a certain movement of the switch to cause the switch to close with more force and at a greater speed, said second named means operating wholly independently of the first named means but being put into action wholly by movement of the switch, and adding its force to the force of the first named means to cause the switch to close, and means for adjusting the position of parts of the second named means to effect changes in sensitiveness of operation thereof.
11. Repeating fuse apparatus comprising a pair of fuses one of which is normally in circuit, a switch mounted to move toward the other fuse, means connecting the switch and fusible part of the first fuse for holding the switch normally spaced from the second fuse, means for braking the tendency of the switch to move toward the second fuse, and adjustable means acting to increase the tendency of the switch to move as aforesaid, the apparatus functioning when the fuse normally in circuit blows to put the second fuse in circuit after a determinable time interval.
12. Repeating fuse apparatus comprising a pair of fuses one of which is normally in circuit, a switch mounted to move toward the other fuse, means connecting the switch and fusible part of the first fuse for holding the switch normally spaced from the second fuse, means for braking the tendency of the switch to move toward the second fuse, adjustable means acting to increase the tendency of the switch to move as aforesaid, the apparatus functioning when the fuse normally in circuit blows to put the second fuse in circuit after a determinable time interval, and delayed action means operating independently of the other means to accelerate the closing of said switch.
13. Repeating fuse apparatus comprising a pair of fuses one of which is normally in circuit, a switch swingingly mounted between said fuses, a contact member on the second fuse with which the switch is designed to engage, the switch being so mounted as to have a tendency to move toward the contact member but being engaged by the fusible element of the first fuse so that it is held normally spaced from the contact, a spring-actuated delayed-action mechanism rendered normally inoperative by being in a dead center position when the switch is open, and connections between the switch and mechanism whereby it is moved past dead center and thereupon becomes active to force the switch against the contact, whereby the second fuse is put in circuit.
14. Repeating fuse apparatus comprising

a pair of fuses one of which is normally in circuit, a switch swingingly mounted between said fuses, a contact member on the second fuse with which the switch is designed to engage, means connected with the switch for imparting thereto a tendency to close toward the contact member, said latter means being adjustable, a spring-actuated delayed-action mechanism rendered normally inoperative by being in a dead center position when the switch is open, and connections between the switch and said mechanism whereby it is moved past dead center and thereupon becomes active to force the switch against the contact, whereby the second fuse is put in circuit. 15

In testimony that I claim the foregoing as my own, I have hereto affixed my signature.

TOMLINSON FORT JOHNSON, JR.
